THERMALLY OPERATED SECONDARY
BREAKERRalph R. Pittman, Park Hill, and Carroll H.
Walsh, Pine Bluff, Ark.

Application June 28, 1945, Serial No. 602,056

10 Claims. (Cl. 200—116)

1

This invention relates generally to circuit breakers, and in particular to an outdoor type of low voltage breaker adapted for use in connection with the secondary windings of outdoor distribution transformers.

Among the objects of the present invention may be noted the provision of: an outdoor type of secondary breaker construction adapted for mounting on the bushing terminal of an outdoor transformer, and suitable for manipulation with a lineman's switch hook; a secondary breaker having an operating characteristic coordinated with the heating characteristic of an associated transformer; a breaker having a latch lever of semaphore type for visibly indicating when the breaker has automatically opened; a breaker having a snap-action movement when manually opened; a breaker having a trip-free mechanism; a breaker embodying a contact movable about a double pivoted mounting to provide high contact pressure and fast opening movement; a breaker having a resilient stationary contact normally under high pressure to provide energy for opening movement, an integral portion of the stationary contact being formed to provide an arcing contact; and a breaker of simple design, rugged strength and inexpensive construction.

Heretofore secondary breakers have been combined with outdoor transformers, the most popular arrangement being one in which an indoor type of breaker is mounted inside of the transformer tank. This arrangement has the serious defect of inaccessibility, so that inability to close the breaker for any reason renders the transformer useless until it is disassembled and the condition remedied. For example, a breaker inside of a transformer tank and submerged in hot oil cannot be reclosed until the whole mass has cooled, even if the load is reduced, if the necessary thermally-responsive element is embodied in the tripping mechanism. In the meantime, serious results due to the long attendant service interruption may occur. Attempts have also been made to mount housed indoor breakers on the outside of the tank of the transformer, resulting in an expensive construction unadapted to the service requirements. So far as we are aware, no satisfactory outdoor type of secondary breaker having the important advantages present in our invention and necessary to meet the service conditions, has been heretofore constructed.

With the above objects in view, our invention resides in the novel features of design and disposition of the various constituent elements, and in the novel apparatus provided by our combina-

2

tion of our breaker with an outdoor transformer, and the scope of the invention will be indicated in the appended claims.

An embodiment of the invention is illustrated in the accompanying drawing, in which: Fig. 1 is a side elevational view of the breaker, shown partly in section; Fig. 2 is a sectional view of the breaker, taken along the line 2—2 of Fig. 1; Fig. 3 is another sectional view of the breaker, taken along the line 3—3 of Fig. 1; Fig. 4 is another sectional view of the breaker, taken along the line 4—4 of Fig. 1; Fig. 5 illustrates the combination breaker and transformer, showing the breaker in the open position; and Fig. 6 fragmentarily illustrates in plan the supporting and connecting structure.

Referring to the details of construction illustrated in Figs. 1 through 4, a block 26, of weather-resistant insulating material, such as porcelain, has mounted thereon the metal supporting member 13, by means of the bolts 27. The supporting member 13 embraces respective opposing sides of the block 26, and is formed to provide a pair of arms 14 and 15, extending in parallel relationship downwardly and outwardly beyond the block 26. The member 13 also extends upwardly above and across the top of the block 26 in vertical spaced relationship therewith. Preferably the supporting member 13 is formed as a U-shaped piece from a flat strip of copper, the respective arms of which are rigidly bolted to the block 26.

The bayonet-type terminal 10 extends downwardly through the top of the supporting member 13, the flange 11 resting on the bushing insulator 12, the latter serving to insulate the terminal 10 in its passage through the member 13. The bimetallic current-responsive element, shown more clearly in Fig. 3, extends horizontally outward beyond the block 26, from the terminal 10. The bimetallic element includes the bimetallic strip 17, one end of which is connected to and supported by the lower end of the terminal 10 by the nut 18, and the other end of which is connected to and supported from the supporting member 13 by means of the bolt 19, the nut 20, and the metal spacing washer 21. At its outer end, the latch detent 23 extends along the unfastened end of the strip 17, being rigidly attached thereto by the rivets 22, and insulated therefrom by the insulating material 24, which is conveniently formed from a strip of mica. The bimetallic element is so arranged that the latch detent 23 moves upwardly when the strip bends in response to heating. If desired, the cover 16 may be provided over the bimetallic element.

At a point spaced from the supporting member 13, a stationary contact support 31 is mounted at the rear of the block 26, by means of the bolt 29 and the nut 30, the head of the bolt 29 being positioned a substantial distance within the block 26 in the recess 28. The stationary contact support 31 extends both downwardly and upwardly along the rear side of the block 26 beyond the nut 30, and is provided with a threaded opening at its upper end, through which a set screw 32 is extended to engage the rear surface of the block 26, for the purpose of adjusting the position of the downwardly extending portion of the support 31. The stationary contact 33, conveniently formed from a looped strip of resilient-conducting material, such as Phosphor bronze, is mounted on the support 31 by means of the rivets 34, extending outwardly and forwardly therefrom below the lower end of the block 26. For convenience of connection, the stationary contact support 31 extends below the stationary contact 33, and at its lower end is provided with the load terminal 53.

A latch lever 25, formed as a semaphore, is mounted for rotative movement about the pivot 48 on the extended arms 14 and 15, being held midway between the arms by the oppositely disposed spacers 46 and 47, and extending upwardly to normally engage the latch detent 23 of the bimetallic element. The movable contact, including the pair of laterally spaced, inwardly extending legs 36 and 37 joined at their respective outer ends by the operating eye 52 and the rivets 51, straddles and is pivotally mounted on the latch lever 25 for rotary movement about the pivot 48, the latter extending laterally from each side of the latch lever 25 at a point slightly above and inwardly with respect to the pivot 48. The relationship of the pivot points 43 and 48 is such that the inwardly extending portions 35 and 37 of the movable contact engage and resiliently deform the stationary contact 33 when the latch lever 25 is in the normal position in engagement with the latch detent 23. The resilient stationary contact is so formed that when deformed a pressure acting outwardly and upwardly is provided tending to concurrently rotate both the latch lever 25 about the pivot point 48 and the movable contact about the pivot point 43. Normally the engagement of the latch lever 25 with the detent 23 of the bimetallic element restrains rotative movement of the latch lever 25, and engagement of the movable contact with the pivotal mounting of the latch lever restrains rotative movement of the movable contact.

A pair of aligning washers 41 and 42 maintain the alignment of the movable contact with respect to the stationary contact, and the spring 40 is arranged to continuously urge the movable contact and latch lever to jack-knife to the relative positions shown by the broken lines of Fig. 1, or the solid lines in Fig. 5.

The lowermost ends of the arms 14 and 15 are joined and held in the desired spaced relationship by means of the spacing sleeve 49, through which is extended the bolt 50. The sleeve 49 also provides a stop to limit movement of the movable contact, for the purpose of preventing engagement with the terminal 53. If desired, the flexible conductors 44 and 45 may be utilized to directly electrically connect the movable contact to the supporting member 13.

As shown in Figs. 1 and 2, an integral portion 35 of the stationary contact 33 extends outwardly beyond the face of the contact between the legs

36 and 37 of the movable contact to engagement with the sleeve 38, the latter being mounted for rotation about the shaft or pivot 39. In its movement to open position, the ends of the legs 36 and 37 disengage the face of the contact 33 before the portion 35 disengages the sleeve 38, the latter elements constituting an arcing contact arrangement functioning to avoid arc-damage to the principal current-carrying contacts.

10 The apparatus shown in Figs. 5 and 6 includes the breaker in the tripped-open position, which might result from an overload on the transformer winding 55 supplied through the load conductors 59 and 60. In this construction the bushing terminal 57 is insulated from the tank wall 54 by means of the bushing 58, and the breaker is both supported from and connected to the bushing terminal 57 by clamping the bayonet terminal 10 of the breaker between the eye bolt 58 and the terminal 57 (Fig. 6).

The current path through the breaker when in closed position is from the terminal 10 to the bimetallic strip 17, thence to the mechanism support 13, thence through the flexible conductors 44 and 45 to the movable contact, thence through the stationary contact 33 to the other terminal 53.

When a predetermined current passes through the breaker, the bimetallic element moves upward at its outer end, releasing the latch lever 25 for rotative movement about its pivot 48. Under the bias of the resilient contact 33, the movable contact moves about its pivot 43 concurrently with its movement substantially endwise bodily away from the stationary contact 33 about the pivot 43, the breaker assuming the tripped-open position indicated by the broken lines of Fig. 1. Concurrently the spring 40 effects the jack-knifing of the latch lever 25 with respect to the movable contact, and the latch lever semaphorically indicates that the breaker has automatically tripped to the open position. While not essential to operation, it is desirable that the bimetallic element be such that its heating characteristic parallels closely that of the associated transformer.

45 To reclose the breaker, the eye 52 may be urged upwardly with a lineman's switch hook until the latch lever again engages the bimetallic element, as shown in Fig. 1, and then pulled down to engage and seat the contacts. While the movable contact and the latch lever are in folded position, the contacts cannot be engaged, because the movable contact is sufficiently retracted to prevent contact engagement. The contacts are therefore not engaged as the latch lever is latched to the bimetallic element, but only when the eye 52 is pulled down after latching the latch lever. In the event that an excess current passes through the breaker at the instant of contact, the downward pull is in the direction to urge the breaker to open position. Since the spring 40 continuously urges the movable contact to fold against the latch lever, the breaker is trip-free, for the reason that contacts cannot be engaged if these elements are in folded position, and cannot be maintained in any other position unless latched to the bimetallic element.

If it is desired to manually open the breaker, this is accomplished by urging the eye 52 upwardly until the contact-ends of the movable contact pass downwardly over-center of the face of the stationary contact, at which time the spring 40 opens the breaker with snap action. The latch lever does not move when the breaker is manually opened.

75 It may be seen that our breaker is of such

simple and rugged construction that the components may be readily formed of common inorganic materials, such as porcelain, copper and copper alloys, and for this reason is an effective outdoor type of device for the purpose, requiring no container, and functionally capable of accomplishing the objectives stated above.

It is intended that the description and drawing of the preferred embodiment of the invention herein presented will be regarded as illustrative rather than limiting.

We claim, as our invention:

1. A secondary breaker comprising relatively movable contacts including a resilient stationary contact and a contact movable to engagement therewith, said stationary contact when engaged urging said movable contact from closed to open position, a current-responsive element in series circuit relation with said contacts, a latch lever pivotally mounted at one end and releasably engaged with said current-responsive element at the other end, means pivotally mounting said movable contact on said latch lever adjacent said one end and relatively remote from the other end, said latch lever being urged to rotary movement through its pivotal connection with said movable contact when said movable contact is engaged with said resilient stationary contact and rotating about said one end concurrently with rotary movement of said movable contact about the pivotal mounting of the latter to open circuit position in response to the occurrence of a predetermined current through said current-responsive element.

2. A secondary breaker comprising a block of insulating material, a supporting member of conducting material fastened at the respective sides of said block, said supporting member extending upwardly therefrom and across the top of said block in spaced relationship therewith and downwardly and forwardly beyond the lower end of said block, a terminal extending downwardly through the top of said supporting member in insulated relationship therewith, a bimetallic element connected in series relationship between said terminal and said supporting member, a contact support fastened at the back of said block and extending downwardly therefrom, a resilient stationary contact carried by said contact support, a latch lever pivotally mounted on the forwardly extending portions of said supporting member and normally extending upwardly to engagement with said bimetallic element, a movable contact pivotally mounted on said latch lever and normally engaging said stationary contact, said latch lever being normally urged for rotary movement by said stationary contact through said movable contact and released for rotary movement in response to a predetermined movement of said bimetallic element.

3. A secondary breaker comprising a block of insulating material, a supporting member including a pair of outwardly and downwardly extended arms embracing and fastened to said block, a contact support fastened to said block in spaced insulated relationship with said supporting member, a bimetallic element carried by said supporting member, a resilient stationary contact mounted on said contact support, a latch lever pivotally mounted between the extended arms of said supporting member and extending upwardly to normally latched engagement with said bimetallic element, a movable contact including a pair of legs straddling said latch lever and normally extending to engagement with said

stationary contact, said movable contact being pivotally mounted on said latch lever adjacent to and above the pivotal mounting of said latch lever, the arrangement being such that both said latch lever and said movable contact rotate about the pivotal mounting of said latch lever concurrently with the rotation of said movable contact about its pivotal mounting on said latch lever under the bias of said resilient contact when said latch lever is unlatched.

4. In a secondary breaker having a pivotally mounted latch lever normally releasably latched to a bimetallic element, a resilient stationary contact, a movable contact having legs straddling said latch lever pivotally mounted thereon and extending to engagement with said resilient contact, said resilient contact normally urging said movable contact toward rotary movement about both pivotal mountings in a direction away from said resilient contact, the movement about the pivotal mounting of the latch lever being normally restrained by engagement with said bimetallic element and the movement about the pivotal mounting of said movable contact being normally restrained by engagement of a portion thereof with the pivotal mounting of said latch lever.

5. In a secondary breaker having a pivotally mounted latch lever, a resilient stationary contact having an outwardly-curved face, a movable contact extending on each side of said latch lever pivotally mounted thereon, said movable contact extending inwardly to engagement with said stationary contact so that said movable contact is urged for movement in one direction away from said stationary contact about both pivotal mountings, and means normally restraining said movement of said movable contact, the pivotal mounting of said movable contact being so related to said resilient contact that said movable contact passes over-center along and disengages said resilient contact when said movable contact is rotated in the direction opposite to said one direction, and resilient means urging the movement of said movable contact in said opposite direction to provide snap-action opening when said movable contact passes over-center of the face of said stationary contact.

6. In a circuit breaker having a pivotally mounted latch lever normally releasably latched to a current-responsive element, a stationary contact, a movable contact pivotally mounted on said latch lever and normally extending to engagement with said stationary contact, one of said contacts being resilient and effective for rotating said movable contact in one direction away from said stationary contact when said latch lever is unlatched for providing a tripped-open position, and means operative in response to manual rotation of said movable contact from the engaged position in the other direction for providing a manually-open position.

7. In a circuit breaker having a pivotally mounted latch lever normally releasably latched to a current-responsive element, a stationary contact, a movable contact pivotally mounted on said latch lever and normally extending to engagement with said stationary contact, one of said contacts being resilient and effective for rotating both said latch lever and said movable contact in one direction when said latch lever is unlatched for providing a tripped-open position visibly indicated by the altered position of said latch lever, and means operative in response to manual rotation of said movable con-

act in the other direction without movement of said latch lever for providing a manually-open position.

8. A secondary breaker comprising relatively movable contacts including a deformable stationary contact of resilient conducting material, a contact movable to engage and deform said stationary contact, said stationary contact when deformed providing the only force urging the movable contact from closed to open circuit position, and latch means including a bimetallic strip under tension for normally restraining the movement of said movable contact to the open position, said latch means releasing said movable contact for actuation to the open position in response to a predetermined bending movement of said bimetallic strip.

9. A secondary breaker comprising relatively movable contacts including a deformable stationary contact of resilient conducting material, a contact movable to engage and deform said stationary contact, said stationary contact when deformed acting to urge said movable contact from closed to the open position, adjustable means for manually regulating the deformation of said stationary contact, and latch means including a bimetallic strip under tension for normally restraining the movement of said movable contact to the open position, said latch means releasing said movable contact for actuation to the open position in response to a predetermined bending movement of said bimetallic strip.

10. A secondary breaker comprising relatively movable contacts including a deformable stationary contact of resilient conducting material

and a movable contact pressed against the stationary contact and extending outwardly therefrom, latch means including a bimetallic element normally holding said movable contact in engaged position, said latch means including a lever pivotally mounted at one end thereof, the other end of said lever releasably engaging said bimetallic element, said movable contact being pivotally mounted on said lever intermediate its respective ends and guided for movement therewith to disengage said stationary contact in response to a predetermined movement of said bimetallic element, said movable contact concurrently pivoting about its pivotal mounting and swinging away from said stationary contact.
